UNITED STATES PATENT OFFICE.

EDWIN J. HICKSON, OF BUTLER, PENNSYLVANIA.

DESIGN FOR A BED-MOUNT.

49,307.

Specification for Design.

Patented July 4, 1916.

Application filed March 9, 1916. Serial No. 83,207. Term of patent 7 years.

To all whom it may concern:

Be it known that I, EDWIN J. HICKSON, a citizen of the United States, and residing at Butler, in the county of Butler and State of Pennsylvania, have invented a certain new, original, and ornamental Design for a Bed-Mount, of which the following is a specification, reference being had therein to the drawings forming a part thereof, in which—

Figure 1 is an elevation of the mount, and Fig. 2 a plan view of the same.

The mount is commonly known as a husk, and comprises an ornament for the rods or bars of a metallic bed frame, the mounts being tubular and adapted to be secured to the rods or bars which extend therethrough.

I claim:

The ornamental design for a bed mount, substantially as shown and described.

EDWIN J. HICKSON.
